US0D1099247S

(12) **United States Design Patent** (10) **Patent No.:** **US D1,099,247 S**
(45) **Date of Patent:** ** *Oct. 21, 2025

(54) **INFLATABLE DEVICE**

- (71) Applicant: **FUNBOY, Inc.**, Seattle, WA (US)
- (72) Inventors: **Blake Miller Barrett**, Seattle, WA (US); **Maxwell Page Barrett**, Seattle, WA (US)
- (73) Assignee: **FUNBOY, Inc.**, Seattle, WA (US)
- (*) Notice: This patent is subject to a terminal disclaimer.
- (**) Term: **15 Years**
- (21) Appl. No.: **29/969,213**
- (22) Filed: **Oct. 21, 2024**

Related U.S. Application Data

- (63) Continuation of application No. 29/879,083, filed on Jun. 30, 2023, now Pat. No. Des. 1,048,278.
- (51) **LOC (15) Cl.** **21-03**
- (52) **U.S. Cl.**

(57) **CLAIM**

The ornamental design for an inflatable device, as shown and described.

DESCRIPTION

FIG. 1 is a top, front, right-side perspective view of an inflatable device, showing the new design;
FIG. 2 is a bottom, back, left-side perspective view thereof;
FIG. 3 is a front view thereof;
FIG. 4 is a back view thereof;
FIG. 5 is a right-side view thereof;
FIG. 6 is a left-side view thereof;
FIG. 7 is a top view thereof;
FIG. 8 is a bottom view thereof;
FIG. 9 is a top, front, right-side perspective view showing the inflatable device in use;
FIG. 10 is a front view thereof; and,
FIG. 11 is a right-side view thereof.

The dashed broken lines depict environment and portions of the inflatable device that form no part of the claimed design. The dot-dashed broken lines represent boundaries of the claimed design and form no part of the claimed design.

1 Claim, 11 Drawing Sheets

US D1,099,247 S
